SERVING FORK WITH SPRING-RETRACTED EJECTOR PLATE

Filed July 12, 1946

By

Clarence A. O'Brien
and Harvey B. Jacobson
Attorneys

depending parallel tines, a socket integral with said head and positioned on the lower end of said shank, an operating rod reciprocably mounted in said hollow shank and bent at its upper end to extend laterally of said rod and through the slot in said shank, a finger engaging operating head on the outer end thereof, a pusher plate on the lower end of said rod extending laterally of said rod and in a direction opposite from the bent portion of said rod, and said pusher plate being disposed between said tines for longitudinal movement therebetween, a washer supported on said rod; and a coil spring disposed about said rod between said washer and said head member for holding said pusher plate

in normally raised or retracted position, and a portion of said handle overlying said slot and engaged by said bent portion of said rod thereby forming a stop limiting the upward movement of said rod in said hollow shank.

WILLARD E. BECKER.
